UNITED STATES PATENT OFFICE.

FRANK L. HOLT, OF FALLS CITY, NEBRASKA.

OILER FOR LOCOMOTIVE-WHEEL FLANGES.

1,175,264.

Specification of Letters Patent. Patented Mar. 14, 1916.

Application filed November 3, 1915. Serial No. 59,463.

To all whom it may concern:

Be it known that I, FRANK L. HOLT, a citizen of the United States, residing at Falls City, in the county of Richardson and State of Nebraska, have invented certain new and useful Improvements in Oilers for Locomotive-Wheel Flanges, of which the following is a specification.

This invention relates to appliances for 10 ciling or lubricating the flanges of wheels of locomotives and the like, for the purpose of insuring smoother travel on curves, making such travel safer by diminishing chances of derailment, increasing tire mileage and 15 reducing tire maintenance and diminishing wear and tear on the rails at curves and on switches and frogs.

My prime object is to produce a fluid pressure wheel flange oiler which can not freeze 20 and be thereby rendered inoperative.

Another object is to produce an oiler which is throttle-controlled; is set to operate at a predetermined pressure; insures free 25 flow of oil at all times when needed regardless of temperature conditions, and which will automatically clean the valve seat each time the throttle is closed.

A further object is to produce a flange oiler of simple and inexpensive construction 30 and which can be installed at low cost.

With these objects in view the invention consists in certain novel and peculiar features of construction and organization as hereinafter described and claimed; and in 35 order that it may be fully understood reference is to be had to the accompanying drawing, in which—

Figure 1, is a diagrammatic elevation showing the relation between a flange oiler 40 embodying my invention and a wheel to be lubricated thereby. Fig. 2, is a full-sized central vertical section of the oiler. Fig. 3, is a horizontal section on the line III—III of Fig. 2. Fig. 4, is a horizontal section on 45 the line IV—IV of Fig. 2. Fig. 5, is a section of a nozzle for the oiler. Fig. 6, is a fragmentary perspective view of the valve of the oiler. Fig. 7, is an inverted plan view of the valve-seat plug of the oiler.

Referring to the drawing in detail, 1 indicates the body or cylinder of the oiler, the same being provided with a piston chamber 2, and a tubular internally threaded neck 3 of smaller diameter than the piston cham-

ber. 4 indicates an oil receiving chamber 55 at the lower end of the neck and 5 one or more discharge passages.

Secured in the upper end of the piston chamber is a collar 6, the same being shown as provided with holes 7, for the reception 60 of a device for screwing said collar into or out of position, and screwed into the collar is a tubular plug 8.

9 indicates a downwardly tapering tubular valve seat plug establishing communication between the interior of the neck 3 and the passage or passages 5, the lower end of the bore of said plug being enlarged or flared as at 10. Within the chamber 4, said plug is formed with side cuts or openings 11 70 which intersect the bore of the plug, the lower sides of said cuts sloping upward so as to produce knife-edge valve seats 12, and in the plane of the chamber 4, the body is provided with perforated enlargements or 75 bosses 13.

Engaging the threads of the neck are externally threaded nuts or collars 14 and 15, provided with radial holes 16, whereby the nuts may be engaged for adjustment purposes, the neck being provided with an opening 17 through which a suitable rod or tool may be introduced for engagement with said holes to effect the adjustment of said nuts. These nuts or collars are fitted in place by 85 screwing them downward into the neck from the chamber 2 until they are accessible through the opening 17. A nut 18 is screwed into the upper end of the neck and a packing 19 is interposed between said nut 90 and nut or collar 14. A packing 20 is also interposed between nut 15 and the valve seat plug and guards against upward movement of said plug 9.

The body is provided with a steam inlet 95 21 communicating with the lower end of chamber 2, and fitting in said chamber is a piston 22 provided with steam packing rings 23 engaging the wall of the chamber, and also with a steam chamber 24 with which 100 inlet 21 communicates when the piston occupies its most depressed position.

The piston is provided with a tubular stem 25 extending slidably through the plug 8, the upper end of the bore of said stem 105 being threaded at 26, and fitting around said stem and bearing at its opposite ends against the piston and plug 8, is a spring 27, the

same being under compression so that when unopposed it shall hold the piston in its most depressed position.

28 indicates a valve rod extending through 5 the piston and its stem and through the nuts mentioned and the packings, and into the valve seat plug to a point below the valve seats thereof, said rod being tubular from its lower extremity to a point above nut 18, and at the last-mentioned point provided 10 with an opening 29 so that steam supplied through the inlet 21 is free to pass into said opening and down through the valve rod. The upper end of the rod is externally 15 threaded at 30 and engaged with the threads 26 of the piston stem, and at its upper extremity is formed with a head 31 whereby it may be engaged with a wrench or other tool and turned to effect downward or upward movement 20 of the valve rod, it being also understood that movement of the piston likewise imparts reciprocatory movement to the valve rod. To guard against accidental movement of the valve rod, a lock nut 32 is 25 mounted upon its threaded portion and engages the upper end of the stem of the piston. The lower end of the valve rod is provided at its outer side with one or more V-shaped kerfs 33, which kerfs lie wholly below 30 the valve seats 12 when the piston is in its most depressed position, at which time the oiler is inoperative. When steam is supplied to the piston chamber and raises the piston the valve rod is elevated so as to 35 bring the kerfs 33 into communication with the oil-receiving chamber 4, the oil is drawn by the force of the steam down through the kerfs under the injective force of the steam, and in order that in this action the oil may 40 be thoroughly divided up into a fine spray or atomized, foraminous partitions 34 occupy the flared opening 10 of the valve seat plug, being stretched across in such manner that they do not interfere with downward 45 adjustment of the valve rod but will intercept and prevent oil from flowing down through the kerfs or leaking down around the valve rod when in inoperative position without being subdivided at passage through 50 said perforations.

Any convenient means may be employed for supporting the oiler at a convenient point with respect to the wheel or wheels to be oiled, that shown consists of a bracket 55 35, for attachment to the locomotive at a convenient point, a threaded plug 36, secured to the oiler and extending through the bracket, and a retaining nut 37 screwed on the plug and engaging the bracket.

38 indicates a short pipe secured to the oiler in communication with the inlet 21 thereof, and coupled in any suitable manner to the steam supply pipe 39 leading from the throttle or its equivalent, not shown.

40 indicates an oil supply pipe screwed

into one of the apertured bosses communicating with chamber 4 and leading from a suitable oil supply tank, not shown. The bosses are disposed at opposite sides so that the supply pipe may be connected with the 70 most convenient one, the other one being closed by a removable screw plug 41. By removing this plug access can be had to the oil receiving chamber for clean out purposes.

42 indicates short pipes communicating with passages 5, and 43 pipes leading from pipes 42 to the wheel flanges to be oiled or lubricated, each pipe 43 terminating in a nozzle 44 which sets at an angle to the flange 80 as shown in Fig. 1, so that it shall discharge the lubricating fluid directly upon the flange and not upon the tread of the wheel where it would reduce the tractive power of the latter.

In practice it is desirable to use an oil 85 containing a heavy asphaltum base, as the asphaltum will adhere to and coat the flange in a more satisfactory manner than can be effected with a light oil.

With the parts arranged as shown, the 90 opening of the throttle results in the passage of steam into chamber 2 and through the valve rod, the pressure thus produced in said chamber raising the piston and the valve rod until the kerfs 33 of the latter are opposite the valve openings 11. As this occurs the injective force of the steam issuing from the lower end of the piston rod draws oil from the chamber 4 down through the kerfs where it mixes with and is atomized by the 100 steam, this action being rendered more thorough as the expansion of the steam in the flared end of the plug 8, compels the greater proportion of the oil to pass through the foraminous partitions 34. The mixture of 105 the steam and atomized oil as an oily vapor passes through the passage or passages 5 and the connections described, to the nozzle or nozzles 44, and is discharged thereby against the flange or flanges of the wheels to be 110 oiled. The asphaltic base of the oil adheres to the flange because it is of such character that it has but little tendency to flow and also because centrifugal force tends to effect its outward flow toward the periphery of the 115 flange or flanges of the wheels.

When the throttle is closed, the spring 27 reseats the piston and cuts off the supply of oil by lowering the valve rod until its kerfs are below the oil chamber 4. It will thus be 120 seen that if a gravity oil feed is employed, there can be no escape of oil when the steam pressure is cut off.

If the engine is to be used mainly for yard and switching purposes and hence operated under light steam pressure, the plug 8 will be partly unscrewed to relax the tension and reduce the resistance of the spring so that the piston may readily rise under reduced steam pressure, and if it is not desired 130

that the oiler shall operate the plug 8 is screwed farther home to increase the tension of the spring sufficiently to hold the piston stationary at its most depressed point of adjustment. The adjustment of the plug 8, 5 may be such as to permit the piston to operate under normal steam pressure on the road or the light pressure ordinarily required for yard operations.

10 Should the oil tend to clog the valve openings 11, the upward movement of the rod 28, incidental to the opening of the throttle will loosen the clogging matter, it being apparent that the heat of the rod due to the flow 15 of steam therethrough, will tend to soften clogging or coagulated oil and thus aid in keeping the valve openings 11 unobstructed. The fact, that the seats 12 are sharp or knife-edged, must also be given consideration, 20 as such seats afford no support upon which clogging matter can find substantial support. Should steam leak past the throttle into chamber 2, it has free passage to the atmosphere and hence cannot condense and 25 render the oiler inoperative.

From the above description it will be apparent that I have produced a wheel flange oiler embodying the features of advantage enumerated as desirable in the statement of 30 the objects of the invention, and while I have illustrated and described the preferred embodiment of the invention, it is to be understood that I reserve the right to make all changes falling within the spirit and scope 35 of the appended claims.

I claim:—

1. The combination with a steam supply and an oil supply, of a tubular plug, having an opening or openings communicating 40 with said oil supply, a valve rod extending through the plug and normally closing said opening or openings thereof, and provided with a kerf or kerfs below said opening or openings, means to receive the pressure of 45 steam to raise the rod until its kerf or kerfs communicate with the said opening or openings, and means for restoring the pressure-receiving means and rod to normal position when the steam pressure is cut off.

50 2. The combination with a steam supply and an oil supply, of a tubular plug, having an opening or openings communicating with said oil supply, a valve rod extending through the plug and normally closing said 55 opening or openings thereof, and provided with a kerf or kerfs below said opening or openings, means to receive the pressure of steam to raise the rod until its kerf or kerfs communicate with the said opening or openings, and a spring to restore the pressure-receiving means and rod to normal position.

60 3. The combination with a steam supply and an oil supply, of a tubular plug, having an opening or openings communicating with 65 said oil supply, a valve rod extending

through the plug and normally closing said opening or openings thereof, and provided with a kerf or kerfs below said opening or openings, and a yieldingly-advanced piston connected to the said rod and adapted to be 70 repressed by steam pressure, to raise said rod until communication is established between the kerf or kerfs thereof and the oil supply.

4. The combination with a steam and an 75 oil supply, of a tubular plug having a valve opening in communication with the oil supply, and a flaring mouth, a foraminous partition in said mouth, a valve rod extending through the plug and normally closing said 80 opening and provided with a kerf, means to receive the pressure of steam to raise the rod to establish communication through said kerf between said opening and flaring mouth of the tube, and means to return the parts to 85 normal position when the steam supply is cut off.

5. The combination with a steam supply and an oil supply, of a tubular valve rod 90 extending through the plug and provided with an external kerf at its lower end and adapted for discharging steam at its lower end, and yielding means connected to said valve rod and adapted under pressure of steam to raise said rod until its kerf establishes communication between the opening 95 and mouth of the tubular plug.

6. The combination with a steam supply and an oil supply, of a tubular plug having 100 an opening in communication with the oil supply, a cylinder in communication with the steam supply, a tubular rod in communication with the cylinder, and extending through the tubular plug and provided with an external kerf which is normally beyond 105 the opening of the plug, a piston in the cylinder, connected to the said rod, and adapted to be raised by steam supplied to the cylinder, and a spring to return the piston to normal position, when the steam pressure is 110 cut off.

7. An oiler, having a steam chamber, an oil chamber, a neck connecting said chambers, and provided with a side opening, a tubular valve plug extending through the 115 oil chamber and provided with a side opening forming a knife-edged valve seat, a collar set into the upper end of the steam chamber, a plug adjustable in the collar, a piston in the steam chamber, provided with a tubular stem extending slidably through the last-named plug, a pair of packings in said neck one above and the other below the opening in the neck, a nut adjustable in the neck, accessible for operation through the 120 opening in the side of the neck, for compressing one of said packings, upon the tubular plug, a pair of nuts adjustable in the neck for compressing the other packing, one of said pair of nuts being accessible through 125 130

said neck opening and the other through the steam chamber, a valve rod extending adjustably through the stem of the piston, and nuts and packings and said valve plug and provided with an external kerf and an opening in communication with the steam chamber below the valve, and closed above said opening; means to lock the rod against accidental adjustment, and a spring for holding

the piston depressed with the kerf of the rod 15 below the opening of the valve-plug, when the steam supply is cut off.

In testimony whereof, I affix my signature, in the presence of two witnesses.

FRANK L. HOLT.
